LIGHT SIGNALING ARRANGEMENT

Karl Meyer, Berlin-Charlottenburg, Germany,
assignor to Orenstein & Koppel Aktiengesell-
schaft, Berlin, Germany

Application April 13, 1931, Serial No. 529,770
In Germany April 16, 1930

1 Claim. (Cl. 177—339)

Light signals for use in day time, which are preferred to the older semaphore signal on account of greater visibility especially in dull weather and on account of giving the same signals by day and night, are required to operate without any break in order to avoid the signal disappearing entirely when it changes from red to green and therefore being overlooked by the driver of a passing train. It is therefore necessary that the green light should light up before the red light is extinguished and vice versa. Similarly the red light must appear immediately if the green light goes out for any reason, for example if the lamp burns out.

These requirements have been found necessary for safety in railway operation and therefore a number of more or less complicated circuits have been developed. In most cases these circuits operate with a number of relays which are interposed in the circuits of the signal lamps and allow their armatures to drop when there is no current in the winding. Their armature contacts control further circuits and cause the signal lamps to be actuated automatically and immediately. The disadvantage of these circuits lies in the use of movable parts and in the wear of the lower contacts. This is found inconvenient when the relays are installed in the open air, as is the case in automatic plants for the block system. The maintenance considerably extends and undesirable interruptions in working have to be taken into account.

Circuits have already been proposed in which the red light is extinguished by a so-called stray transformer by a winding through which the green current flows nullifying the voltage in the red circuit. The disadvantage in this case is the unfavorable ratio between the loads on the red circuit and the green circuit which prevents any considerable extension of this system. A known circuit operates with a relay which is excited by the green current and when the armature is attracted, simply short circuits the red lamps. The short circuit current flowing through the short circuit contacts is taken into account and is limited by special means to a maximum value. This means, however, fails if the relay is sluggish and does not let its armature fall.

In the following a circuit is described which is suitable for semi- and completely automatic light signaling plants and which can be employed with advantage while the above-mentioned drawbacks are avoided. Its advantage consists principally in that it only employs apparatus at rest and therefore is extremely certain in operation. It is

also characterized by great simplicity and cheapness together with very high efficiency.

The circuit depends on the fact that phase displaced currents act on one another with inductive or capacitative coupling.

The invention is illustrated diagrammatically in the accompanying drawing, in which:

Fig. 1 is a diagrammatic view of a light signaling arrangement in accordance with the invention.

Fig. 2 is a vector diagram illustrating the mode of operation of the invention.

Fig. 3 is a view similar to Fig. 1 illustrating a modification of the invention.

In Fig. 1 the green current branch comprising the choke coil D, the green lamp F, the switch S and the condenser C₁, is connected to the phase R—S of a three phase supply R—S—T, and the red current branch consisting of the choke coil D which is common to both circuits, the red lamp H and the condenser C₂ is connected to the phase R—T. The absolute magnitudes of the resistances D, C₁ and C₂ are to be taken as equal or nearly equal to the working resistance of the signal lamps F and H. These lamps take the same amount of power.

If the switch S is closed the green current J_F flows in its full strength through the green lamp F. The red current J_H in the red branch is then so reduced that the red lamp H is completely extinguished. When the switch S is opened the red lamp H burns brightly.

The red lamp is extinguished by the inductive voltage drop in the inductance D which is common to both branches and which is produced by the green current which is ahead of the red branch voltage R—T. The mode of operation will be seen from the vector diagram shown in Fig. 2.

The current and voltage conditions in the structural example according to Figure 1 which result when the line clear circuit switch S is closed are shown in Figure 2. E₁, E₂ and E₃ represent the separate phase voltages of the multiphase network, namely a three-phase network according to magnitude and phase position. The values inserted in the diagram were calculated under the assumption that the "blind" resistances (reactances) of the choking coil D₁ and the condensers C₁ and C₂ as well as the actual effective resistances of the lamps F and H (in a warm state) are equivalent with respect to their absolute amounts.

The total value of the currents flowing over the branches with the signal lamps F and H is

characterized by the vector J_D . The vector J_D is split up into the two components J_H and J_F ; the current component J_H is substantially smaller than the component J_F and the corresponding current is not sufficient to light up the "stop" lamp. The vector of the voltage $e_D = e_{0-R}$ induced by the apparent current J_D in the choking coil D_1 common to both lamp branches is disposed vertically to the vector of the current J_D and combined with the vector of the network voltage $E_2 = E_{R-T}$ so that there results for the danger current branch, the voltage according to the vector e_{T-O} . This vector is again split up into the two components $J_H \cdot X_{C2}$ and $J_H \cdot R_H$. The voltage component $J_H \cdot R_H$ corresponds to the voltage at the terminals of the "stop" lamp H . Its absolute value is only a fraction of the absolute value of the network voltage and is not capable of lighting up the "stop" lamp. Vice versa the vector of the choking coil voltage e_D in combination with the vector of the phase voltage $E_1 = E_{S-R}$ constitutes the vector of the voltage e_{S-O} at the line clear current branch, the voltage corresponding to the effective components $J_F \cdot R_F$ being at the terminals of the line clear lamp F .

If the inductive resistance of the choking coil D_1 is so proportioned that in conjunction with the capacity resistance of the condenser C_1 and the effective resistance of the lamp F it produces a lag of the current J_D of 30° relative to the phase voltage $E_1 = E_{S-R}$ and moreover, if the absolute value of the inductive voltage drop in the choking coil D_1 is equal to the absolute value of the three-phase voltage, the voltage at the terminals of the "stop" lamp will be equal to zero, because the vector $e_D = e_{0-R}$, which is disposed vertically to the vector J_D , will coincide with the phase voltage of the vector $E_2 = E_{R-T}$ so that the voltage e_{T-O} at the terminals of the "stop" lamp has become equal to zero. The lamp H is absolutely without current. When the line clear circuit is open, the "stop" light H shines with full strength or intensity because the capacity resistance of the condenser C_2 in conjunction with the inductive resistance of the choking coil D_1 and also the ohmic resistance of the lamp H produces such an apparent resistance

that the rated current flows through the lamp H .

It will be understood that the value of the condensers and inductance may vary within certain limits and the following values in numerical terms is given by way of example:

The line clear lamp F and the stop lamp H have each an output of 60 watts and consequently a current of 0.5 ampere with 120 volts and a resistance of 240 ohms. The choke coil in the common branch possesses an apparent resistance of 278 ohms, that is to say, at 50 Hertz an inductivity of 0.89 henry. In the line clear lamp branch, the condenser has a capacity of 24 microfarads with an apparent resistance of 139 ohms and the same applies to the condenser in the stop lamp branch. The voltage of the system amounts to 139 volts with a periodicity of 50 Hertz.

The operation of the system or arrangement will not be affected by replacing the choking coil with a condenser and the condensers with choking coils (Fig. 3).

What I claim is:

An electric light signaling arrangement having a red lamp and a green lamp, the red lamp being adapted to be lighted when the green lamp is dark and vice versa wherein the signal currents are of different phases comprising a polyphase feed system, conductor means common to the two lamps and connected with one conductor of said system, a second conductor means, said second conductor means including separate connections between said lamps and the remaining conductors of the polyphase feed system, means including an impedance in the common conductor 80 for causing a phase displacement of the voltage and current therethrough, means including an impedance in the separate connections for causing a phase displacement of the voltage and current therethrough opposite to the first mentioned 40 displacement, said impedances being constructed to have such values that in their particular arrangement the current through one of the lamps will be insufficient to illuminate it except when the circuit through the other lamp branch 45 is broken or opened.

KARL MEYER.
